9 Claims. (Cl. 210—255)

ABSTRACT OF THE DISCLOSURE

This invention provides a sample conditioning unit especially designed to filter samples analyzed in automatic analytic apparatus, with the unit being a relatively inexpensive plastic block construction providing a plurality of side-by-side chambers suitable for holding samples during preliminary steps and a filtering chamber adapted to hold a filter; the block being constructed with a passage formed in the housing of the block in such way that the passage extends from the bottom of one chamber to a central location at the top of the chamber adapted to carry out the filtering, and with the filtering chamber being removable for easy access to clean the unit and replace the filter.

The present invention relates to improvements in a sample conditioning unit, and more particularly to such a unit adapted to provide a separation of a component in automated analytical equipment.

Many types of chemical analyses require the processing of a great number of samples of similar character. The repetitive performance of similar operations lends itself to automation, and the use of automatic analyzing equipment can result in a material savings in the time of the operator. In addition, the automated equipment provides more uniform procedures with greater accuracy and greater economy through the unattended operation.

However, it is important to use definite fixed analytical procedures for carrying out the analyses, and these procedures are carefully worked out to provide a standard which is of value to the person interpreting the analytical results. Accordingly, it is important to adhere to the standards, and therefore certain steps which have been difficult to automate in simple equipment must be automated in order to achieve the objectives of the present invention.

One of the steps often used in analytical procedures is the separation of a constituent of a sample, and a typical procedure involves the precipitation and filtration of the constituent. It has been proposed to effect such separation by means of automated centrifuging devices, but such a unit requires a rather complicated mechanism.

In order to provide a unit suitable for automated analytic equipment where filtering or conditioning is achieved by passing the sample through filter paper or other media, a sample conveying and conditioning unit has been developed which is the subject of a copending United States patent application Ser. No. 207,122 filed July 2, 1962, now patent number 3,282,431, by Hans Baruch and Dalny Travaglio, and assigned to the same assignee as the present invention. While the application cited above describes a unit which is eminently satisfactory for its purpose, it has been found that certain improvement may be made thereon, and the present invention is directed to such improvements.

In its preferred form, the invention relates to an improved filtering device suitable for automatic filtration,

2

but in its broad form, other means for conditioning sample as it passes therethrough can be used. For example, an ion exchange resin could be used to effect a desired change on the sample, or the sample could be contacted with activated charcoal or an activated refractory material or ceramic filter to remove certain materials from the sample. The sample may also be treated with filter aids such as diatomaceous earth.

The invention also provides a unit where precipitation or other treatments are effected while the unit is conveyed through an automated system, and this provides a control of the time duration, and allows for other treatments to be provided by the automated equipment. A more complete disclosure of automated equipment which may use the sample conveying and conditioning unit of this invention is given in the copending United States patent application cited above and the applications cited therein. Accordingly, this structure will not be described in detail herein.

It is a primary object of this invention to provide an improved unit capable of conveying and conditioning samples, and particularly a unit capable of separating constituents from samples as they are carried through analytical procedures in an automated analytical system, in which an improved transfer of sample is provided together with decreased cross-contamination between samples.

Another object of the invention is the provision of an improved unit of the character described which is capable of providing a rapid filtration in an automated system in a manner similar to the operation conducted by a laboratory technician using manual procedures.

A further object of the invention is the provision of a unit of the character described which is composed of a material that is resistant to chemicals, and which is capable of a long useful life.

A still further object of the invention is to provide a sample conveying and conditioning unit which is constructed in parts to provide easy fabrication and improved cleaning, and which can be fitted with a new filter or the like when necessary between operations.

Further objects and advantages of my invention will appear as the specification continues, and the new and useful features of my sample conditioning unit will be fully defined in the claims attached hereto.

The preferred forms of my invention are illustrated in the accompanying drawings, forming part of this description, in which:

FIGURE 1 is a plan view of a preferred form of a sample conditioning unit constructed according to the invention as it appears in operation with automatic equipment;

FIGURE 2, a sectional view of the apparatus shown in FIGURE 1 taken substantially in the plane of line 2—2 thereof;

FIGURE 3, a perspective view of the components of a filter block constructed according to the invention and utilized as a component of the apparatus shown in FIGURES 1 and 2;

FIGURE 4, a sectional view of a portion of the filter block shown in FIGURES 1 through 3 taken substantially in the plane of line 4—4 of FIGURE 2; and

FIGURE 5, a sectional view of a portion of the filter block shown in FIGURES 1 through 3 taken substantially in the plane of line 5—5 of FIGURE 2.

While I have shown only the preferred forms of my invention, it should be understood that various changes

or modifications may be made within the scope of the claims hereto attached, without departing from the spirit of the invention.

Referring to the drawing in greater detail, there is shown in FIGURE 1 a sample conditioning unit 11, comprising one or more filter blocks 12 each having a plurality of laterally spaced open top compartments serving as sample containers, a sample conditioning means, and means for transferring sample from one container to another. The filter blocks may be made of any suitable material, but they are preferably molded from a moldable plastic.

Thus, in the preferred form, the filter blocks 12 are each in the form of a unit having four open top containers or compartments adapted to hold sample material. Container 13 is adapted to receive samples, and the samples are moved progressively across the unit through compartments 14, 16 and 17 as hereinafter explained. Various treatments may be effected on the sample as it moves laterally across the unit, and a separation is carried out as the sample moves from container 16 to container 17.

As best seen in FIGURE 3, the filter blocks 12 are preferably molded in two sections including an upper section 18 and a lower section 19. This construction has the advantage of allowing easy replacement of filter cups 21a within container or compartment 16. In addition, it allows for easy fabrication by molding and better access for cleaning.

In order to hold the two sections together, lugs 22 on the upper section are force fit into holes 23 in the lower section to provide the basic filter block 12. These blocks can be secured together, if desired, to provide larger block units similar to those illustrated in the patent cited above, by fitting connecting rods (not shown) or other fastening means through holes 24 and tying the units together in side-by-side fashion.

The lower block 19 has supports 26 adapter to ride on a conveyor or slide on a track, and depending lugs 27 adapted to fit in engagement with a drive chain or the like to provide accurately indexed driving of the block units. As here shown, a dummy container 25 is also provided, and although it serves no function in the embodiment here shown, other than for reinforcement, it may be used as a container in other applications.

In a typical operation, the samples are conveyed linearly through a plurality of sample stations by a suitable conveyor means, and the treatments necessary to provide the desired analytical procedures are carried out. Preferably, the samples are moved stepwise and the treatments are spaced at selected positions to time the period between operations, as disclosed more completely in the copending United States patent cited above.

As best seen in FIGURE 2, the units are carried on rollers 28, and movement is imparted to the unit by chain 29 which engages lugs 27 on the bottom of the blocks 12. The samples are generally loaded into the compartments or containers 13, and a measured quantity of sample transferred to container 14 along with a precipitating reagent in a transfer device (not shown). The slurry is then transferred into filtering position by a transfer device 31.

The transfer device 31 comprises a support 32 which is adjustable to present the device at any desired sample station, and a cylinder 33 carried by the support and adapted to move vertically into and out of position on container 14 and provide positive pressure therein for effecting transfer of liquid to compartment 16 through connecting channel 34. This connecting channel is an important feature of the present invention because it improves the system shown in the prior patent cited above by reducing cross-contamination between samples and simplifying the construction of transfer device 31.

In the prior patent, an inverted U-tube was used in combination with a pressure head to effect this transfer.

This required a longer stroke of the pressure head in order to move the U-tube end axially from the bottom of the tube to a clearance position. In addition, the U-tube was not always cleaned between handling of each sample, and therefore, the system was restricted in applicability. Both of these problems are solved in the present invention.

The connecting channel 34 is constructed to extend from the bottom of container 14 to a discharge position 36 centrally located in the upper portion of compartment 16. In this way, material is discharged into filter cup 21 where rapid filtration occurs. Preferably the compartment 14 has sloping walls which form a well 37 in communication with connecting channel 34. This allows for rather complete transfer of liquid. If desired, suitable reinforcing structure can be included such as ribs 38, but it is important to fabricate the ribs in such a way that they do not interfere with proper movement of sample.

The cylinder 33 of transfer device 31 comprises a plunger 39 slidably mounted therein so as to move between a sealing position and a clearance position over compartment 14. Plunger 39 has a lower surface 41 adapted to fit in sealing engagement with the top of the container 14 so that on downward movement of the plunger a positive pressure may be applied in the container by controlled air movement through a passage 42 extending through the bottom of the plunger and providing an orifice in the passage. The orifice passage is small enough that a positive pressure builds up within the cylinder to retain downward movement against the spring 43. The orifice also prevents excess pressure from building up in container 14.

In operation, air pressure is provided through line 44, which pressure causes plunger 39 to move downward. As the plunger 39 moves downward, the surface 41 thereof provides a seal in the container 14, and air then passes from within the cylinder 33 down through the orifice into the container to provide a super-atmospheric pressure therein. This pressure then causes liquid to be forced through tube connecting channel 34 so that substantially all of the liquid is removed and forced into the filter cup 21 of compartment 16. When the air pressure is shut off in line 44, the super-atmospheric pressure within the cylinder and within the container is soon reduced and spring 43 forces the plunger 39 back to the clearance position. In this way, the plunger and tube are withdrawn so that the unit 11 may be advanced to the next station.

The slurry delivered into the filter cup 21 passes through the filter and down through a passage 46 into compartment 17. The filter cup 21 is held in the compartment 16 by a sloping floor 47 and axially extending ribs 48. In this way all of the walls of the filter cup assist to provide rapid filtration. Thus separation is effected between the solid precipitate and the liquid filtrate, and the filtrate is carried in the compartments 17 for further treatment and/or transfer to other pieces of equipment for completion of the analysis.

In the unit here shown, the filter cup 21 is constructed of porous paper so that rapid filtration takes place by gravity, and external pressure is not needed. However, it will be appreciated that positive pressure could also be applied to speed up filtration, if desired. Filter cups in the form of that shown in FIGURE 2 are available through regular commercial supply channels, and these units are quite suitable. If desired, cups may be fabricated from ordinary filter paper to provide the cup 21a shown in FIGURE 3.

As indicated above, the four compartments are cleaned between operations, and enough filter blocks 12 are provided so that automated procedure may be conducted continuously, if desired. When the blocks are cleaned, they are broken down into the two sections and the used filter cups discarded. After cleaning, a new filter cup is placed in each chamber 16, and the two sections fit to-

gether. The assembled sections then retain the cup in position until use. The ribs 48 in compartment 16 hold the filter cups away from the chamber wall so that unimpeded movement of filtrate is assured through a large filter surface.

From the above description, it is seen that I have provided a filter unit or the like suitable for use in automated analytical systems. It is also apparent that the unit is simple in construction, and is capable of conducting a filtering step in an automated system in a manner analogous to the manner in which a laboratory technician would carry out the same operation manually.

I claim:

1. A sample conditioning unit for automated analytical apparatus, comprising a housing having a plurality of laterally spaced compartments, a first passage in said housing extending from the bottom of a first of said compartments to a location near the top of a second of said compartments, each of said first and second compartments being laterally disposed to each other and defined by walls internal of said housing, the walls of said first and second compartments defining said first passage, means for moving liquid through said first passage, a second passage in communication between said second compartment and a third compartment for carrying liquids from the second to the third compartment, and conditioning means carried in said second compartment.

2. A sample conditioning unit for automated analytical apparatus, comprising a housing having a plurality of laterally spaced compartments, a first passage in said housing extending from the bottom of a first of said compartments to a location near the top of a second of said compartments, each of said first and second compartments being laterally disposed to each other and defined by walls internal of said housing, the walls of said first and second compartments defining said first passage, a pressure supply device mounted for movement into position on the first compartment to pressurize the compartment and force liquid in the first compartment through said passage to the second compartment, a second passage in communication between said second compartment and a third compartment for carrying liquids from the second to the third compartment, and conditioning means carried in said second compartment.

3. The sample conditioning unit defined in claim 2, in which the housing is composed of a molded plastic containing two sections constructed to provide improved access to the compartments and passages of the unit.

4. A sample conditioning unit for automated analytical apparatus, comprising a housing having a plurality of laterally spaced compartments, a first passage in said housing extending from the bottom of a first of said compartments to a location near the top of a second of said compartments, each of said first and second compartments being laterally disposed to each other and defined by walls internal of said housing, the walls of said first and second compartments defining said first passage, means for moving liquid through said first passage, a second passage in communication between said second compartment and a third compartment for carrying liquids from the second to the third compartment, and a cup-shaped filter carried in said second compartment in position to receive liquid from said first passage.

5. A sample conditioning unit for automated analytical apparatus, comprising a housing having a plurality of laterally spaced compartments, a first passage in said housing extending from the bottom of a first of said compartments to a location near the top of a second of said compartments, each of said first and second compartments being laterally disposed to each other and defined by walls internal of said housing, the walls of said first and second compartments defining said first passage, a pressure supply device mounted for movement into position on the first compartment to pressurize the compartment and force liquid in the first compartment through

said passage to the second compartment, a second passage in communication between said second compartment and a third compartment for carrying liquids from the second to the third compartment, a cup-shaped filter carried in said second compartment in position to receive liquid from said first passage, and a plurality of axially extending ribs on the wall of said second compartment for holding the cup-shaped filter away from the walls of the compartment and improve drainage of liquid that has passed through the filter.

6. A sample conditioning unit for automated analytical apparatus, comprising a housing having a plurality of laterally spaced compartments, a first passage in said housing extending from the bottom of a first of said compartments to a location near the top of a second of said compartments, each of said first and second compartments being laterally disposed to each other and defined by walls internal of said housing, the walls of said first and second compartments defining said first passage, a pressure supply device mounted for movement into position on the first compartment to pressurize the compartment and force liquid in the first compartment through said passage to the second compartment, said pressure supply device including a cylinder having a controlled supply of compressed air and a plunger movable onto said second compartment when the cylinder is pressurized, said plunger having a restricted passage for supplying air at a controlled air pressure in the second compartment, a second passage in communication between said second compartment and a third compartment for carrying liquids from the second to the third compartment, and a cup-shaped filter carried in said second compartment in position to receive liquid from said first passage.

7. The sample conditioning unit defined in claim 6 in which the housing is composed of a molded plastic containing two sections constructed to provide improved access to the compartments and passages of the unit.

8. A sample conditioning unit for automated analytical apparatus, comprising a housing constructed in two sections including an upper section and a lower section, a plurality of compartments in said upper section including a first open top compartment and a second compartment laterally disposed to the first compartment and having an open bottom, a first passage in said housing extending from the bottom of the first compartment to a central location at the top of the second compartment, each of said first and second compartments defined by walls internal of said housing, the walls of said first and second compartments defining said first passage, a pressure supply device mounted for movement into position on the first compartment to pressurize the compartment and force liquid in the first compartment through said passage to the second compartment, a cup-shaped filter carried in said second compartment in position to receive liquid from said first passage, and a third compartment in said lower section in position to receive liquid passing through the filter in said second compartment.

9. A sample conditioning unit for automated analytical apparatus, comprising a housing constructed in two sections including an upper section and a lower section, a plurality of compartments in said upper section including a first open top compartment and a second compartment laterally disposed to the first compartment and having an open bottom, a first passage in said housing extending from the bottom of the first compartment to a central location at the top of the second compartment, each of said first and second compartments defined by walls internal of said housing, the walls of said first and second compartments defining said first passage, a pressure supply device mounted for movement into position on the first compartment to pressurize the compartment and force liquid in the first compartment through said passage to the second compartment, said pressure supply device including a cylinder having a controlled supply of compressed air and a plunger movable onto said second

compartment when the cylinder is pressurized, said plunger having a restricted passage for supplying air at a controlled air pressure in the second compartment, a cup-shaped filter carried in said second compartment in position to receive liquid from said first passage, a plurality of axially extending ribs on the wall of said second compartment for holding the cup-shaped filter away from the walls of the compartment and improve drainage of liquid that has passed through the filter, and a third compartment in said lower section in position to receive liquid passing through the filter in said second compartment.
